UNITED STATES PATENT OFFICE

ADONIRAM J. GREEN, OF WEST CALDWELL, NEW JERSEY, ASSIGNOR TO GENERAL ELECTRIC COMPANY, A CORPORATION OF NEW YORK

THERMAL CUT-OUT

Application filed April 18, 1930. Serial No. 445,492.

My invention relates to thermal cutouts, particularly of the fusible link type such as shown and claimed in the Wright Patent No. 1,265,576, of May 7, 1918.

In the Wright thermal cutout an electrically heated contact post is mounted within an enclosing casing of insulating material together with a cooperating flexible contact which is biased out of engagement with the electrically heated post. A fusible link is provided to interconnect the electrically heated contact post and the flexible contact. With this arrangement the thermal capacity of the electrically heated post provides a desirable time delay in the fusing of the link upon occurrence of overload conditions in the circuit controlled by the cutout. Hence, this form of thermal cutout is particularly advantageous in protecting small motors, such as used on washing machines or other similar devices against injurious overheating or burnout due to stalling, or the like, without however responding to the temporary excessive inrush of current ordinarily occurring when such motors are started.

The fusible link of the Wright thermal cutout is made of two parts, one of the parts being yoke shaped to encircle the electrically heated contact post and the other part being a bar secured across the ends of the yoke by readily fusible solder. In practice difficulty may be experienced upon fusing of the solder due to the separated parts of the link falling into contact with the energized parts of the cutout thus preventing the opening of the circuit and thereby defeating the intended purpose of the cutout.

The principal object of the present invention is to overcome this difficulty by providing means for holding at least the yoke part of the fusible link on the electrically heated post after the link is fused.

In the accompanying drawing, Fig. 1 is a sectional view of the thermal cutout provided with my improved form of fusible link and Fig. 2 is a top view of the cutout.

In Fig. 1 the contact post 10 is mounted within the insulating enclosing casing 11 having the removable top 12. A heater 13 encircling the post 10 serves to heat the post

with a time delay action upon the occurrence of overloads in the circuit protected by the cutout.

The flexible contact 14 is mounted at the bottom of the enclosing casing 11 so as to be biased away from the contact post 10 as indicated by the dotted lines. However, in service the flexible contact 14 is held against its bias by the fusible link 15. Link 15, as more clearly shown in Fig. 2, is formed of a yoke part 16 and a bar part 17, the latter being secured to the ends of the yoke 16 by readily fusible solder.

The cutout is provided with the terminals 18 and 19 which are so connected that the circuit through the cutout extends from the terminal 18 through the heater 13 to the post 10 and then through the fusible link 15 and the spring contact 14 to the terminal 19.

In order to insure that the yoke 16 is held on the post 10 after the bar 17 is released by the melting of the fusible solder, the small projections 20 are punched out from the opposite sides of the yoke 16 so as to extend partially around the post 10 when the link 15 is in its operative position. In this way the yoke 16, which is the part most likely to fall so as to accidentally re-establish the circuit through the cutout after the fusible solder has melted, is maintained in its normal operating position.

After the link 15 is fused by an overload current, the separated parts of the link may be readily removed and a new link inserted in the cutout upon removing the cover 12.

What I claim as new and desire to secure by Letters Patent of the United States is:

1. In an electric cutout, an electrically heated contact post, a contact biased out of engagement with the post, and a two-part fusible link encircling the contact and the post for interconnecting the same and provided with means for holding at least one part thereof on the post after the link is fused.

2. In an electric cutout, an electrically heated contact post, a flexible contact biased out of engagement with the post, and a removable two-part link having a U-shaped

yoke part for encircling the post, and a bar member secured against the ends of the yoke by readily fusible solder for holding the flexible contact against its bias, said yoke having 5 projections punched out from the opposite sides thereof for holding the yoke on the post after the solder is fused.

In witness whereof, I have hereunto set my hand this 16th day of April, 1930.

10
